CONDUCTIVE SHOE

Craig MacQuaid, Clayton, and Leslie R. Heideman, Normandy, Mo., assignors to International Shoe Company, St. Louis, Mo., a corporation of Delaware

Filed July 6, 1959, Ser. No. 825,314

3 Claims. (Cl. 317—2)

The present invention relates generally to the shoe art, and more particularly to a novel conductive shoe incorporating a molded or vulcanized shoe bottom providing a physically continuous electrically conductive construction from the outsole and heel to and including the sock lining contacting the wearer's foot, and to a method of constructing such a shoe.

Heretofore conductive shoes adapted to ground static electricity accumulated in the body of the wearer have long been used in industries where static charges may adversely affect the work efficiency of the workmen, or may set off an explosion, as in operating rooms, powder plants, and other areas. Various improvements have been made in conductive shoes, but one or more disadvantages are inherent in constructions now available. Where conductive cements are used, separations will inevitably occur. Where conductive plugs are used to join parts of the shoe, high or low spots will develop in the shoe which is uncomfortable for the wearer.

Therefore, an object of the present invention is to provide a novel electrically conductive shoe which overcomes the disadvantages inherent in electrically conductive shoes now available for use.

In brief, the present novel electrically conductive shoe includes a molded or vulcanized electrically conductive bottom. In superposed relation are a conductive sock lining, a perforated insole, a perforated shank, a heel filler, and an electrically conductive elastomeric integral heel and outside molded and vulcanized to the lasted upper, filling the perforations of the insole and curing to the sock lining to create an integral, electrically conductive shoe bottom.

Another object of the present invention is to provide a novel electrically conductive shoe incorporating a molded and vulcanized outer sole and heel having integral portions extending upwardly through provided openings in an insole and shank fused with an electrically conductive sock lining.

Another object is to provide a novel electrically conductive shoe incorporating fused electrically conductive material between an electrically conductive sock lining and electrically conductive outer sole providing a continuous electrical circuit for grounding static electricity.

Another object is to provide a novel method of constructing or forming an electrically conductive shoe, particularly the bottom part thereof.

Another object is to provide a novel method of forming predetermined portions of a shoe bottom portion.

Another object is to provide a novel electrically conductive shoe incorporating a continuous integrated physical path for the conduction of static electricity from the wearer to ground.

Other objects are to provide a novel electrically conductive shoe in which the bottom portion is of sturdy construction to provide a continuous electrical path for electricity from the foot of the wearer to ground for substantially the life of the shoe, which is effective for its intended purpose in grounding static electricity, which eliminates juncture planes in the electrical path between the outer sole and sock lining of the bottom portion, and which otherwise fulfills the objects and advantages sought therefor.

The foregoing and other objects and advantages are

2

apparent from the following description taken with the accompanying drawing, in which:

FIGURE 1 is a perspective view of an electrically conductive shoe incorporating the teachings of the present invention;

FIGURE 2 is a plan view of an electrically conductive sock lining;

FIGURE 3 is a plan view of an insole incorporating a plurality of openings;

FIGURE 4 is a plan view of perforated shank;

FIGURE 5 is a side elevational view of the perforated shank of FIGURE 4;

FIGURE 6 is a plan view of a fiber heel filler;

FIGURE 7 is an enlarged fragmentary central longitudinal cross-sectional view through the shoe of FIGURE 1;

FIGURE 8 is a transverse cross-sectional view taken on substantially the line 8—8 of FIGURE 7;

FIGURE 9 is a vertical, transverse, cross-sectional view taken on substantially the line 9—9 of FIGURE 7; and

FIGURE 10 is a vertical, transverse, cross-sectional view taken on substantially the line 10—10 of FIGURE 7.

Referring to the drawing more particularly by reference numerals, 16 indicates generally an electrically conductive shoe including the teachings of the present invention. The shoe 16 includes a conventional upper 18 and a novel shoe bottom 20.

The shoe bottom 20 comprises an electrically conductive sock lining 22, an insole 24 having openings 26 therethrough, a shank 28 having openings 30 therethrough, a fiber heel filler 32, an electrically conductive outsole 34, and an electrically conductive heel 36 integral with the outsole 34. Integral with the outsole 34 and the sock lining 22 are electrically conductive connecting plugs 38 which extend through the insole openings 26 and the shank opening 30, as is clear from FIGURES 7, 8 and 9.

In making the present novel shoe 16, the upper 18 is lasted to the perforated insole 24 on a wooden last by conventional shoe making operations. After the shoe upper has been roughened on the bottom for attaching purposes, the lasted shoe upper is removed from the wooden last and a vulcanizable adhesive is applied to the roughened surface. The electrically conductive sock lining 22 is prepared with a suitable electrically conductive vulcanizable adhesive on the attaching side and is positioned within the shoe against the perforated insole 24. The prepared lasted upper, having the above-mentioned parts and preparation, is placed upon a metal last which is a part of the molding and vulcanizing machine.

The shank 28, and the heel filler 32, are anchored to the bottom of the insole by the struck-out prongs 40 so that the perforations of the shank 28 are aligned with the perforations of the insole 24. Vulcanizable, electrically conductive, elastomeric compound, which is to

be molded to form the outsole 34 and heel 36, is placed within the heated mold consisting of a bottom plate and side rings and the metal last covered by the shoe upper 18 is positioned with respect to the side rings of the mold. The mold is closed, sealing against the lasted upper 18, and heat and pressure applied in the usual manner of molding and vulcanizing equipment to force the heat softened compound through the openings 30 and 26 into engagement with the sock lining 22 to fuse therewith and to become integral therewith. The metal last serves as

the suitable backing element applied against the upper surface of the sock lining 22 and insole 24 to retain the rubber against the exerted pressure. The outsole 34 and the heel 36 are molded to the desired configurations. In the vulcanizing process, they become securely attached to all portions of the insole 24, the shank 28, the filler 32, and the upper 18, which are engaged by the rubber material.

It is clear from the foregoing that a continuous physical electrical path is formed which includes the sock lining 22, the plugs 38, the outsole 34, and the heel 36. There are no adhesively connected planes which may become separated. The aforementioned four elements of the shoe bottom are integral. Hence, for the life of the shoe 16, there is assured an electrical path for discharge of static electricity from the wearer.

It is manifest that the placement, number and size of the openings 26 and 30 may be varied as desired, and that the composition and form of the conductive rubber may be varied.

It is to be understood that the foregoing description and the accompanying drawing have been given by way of illustration and example. It is also to be understood that changes in form of the several parts, substitution of equivalent elements or steps, and rearrangement of parts or steps, which will be readily apparent to one skilled in the art, are contemplated as within the scope of the present invention, which is limited only by the claims which follow.

What is claimed is:

1. An electrically conductive shoe including an insole, perforations in said insole, a sock lining of electrically conductive material, an outsole of electrically conductive material, and electrically conducting plugs ex-

10 tending into said perforations from said outsole, said plugs being integral with said outsole and said sock lining and adapted to conduct static electricity from a wearer into said outsole.

5 2. An electrically conductive shoe including an insole, perforations in said insole, a sock lining of electrically conductive material, a shank having perforations therein secured beneath said insole with the perforations of said insole and shank aligned, an outsole of electrically conductive material, and electrically conducting plugs extending into said perforations from said outsole, said plugs being integral with said outsole and said sock lining and adapted to conduct static electricity from a wearer into said outsole.

15 3. A method of forming an electrically conductive shoe comprising molding to an upper an outsole of electrically conductive material, and integrating an integral portion of said material while fluid with a provided sock lining of electrically conductive material,
